RADIO IMPULSE SYSTEM

Norman H. Young, Jr., Jackson Heights, N. Y.,
assignor to Federal Telephone and Radio Corporation, Newark, N. J., a corporation of Delaware

Application December 15, 1942, Serial No. 469,044

6 Claims. (Cl. 178—44)

1

This invention relates to radio impulse systems and more particularly to systems for selectively filtering pulse modulated waves in accordance with the amplitude of the pulses.

In the copending application of D. Grieg entitled "Receiver system," Serial No. 467,516, filed December 1, 1942, methods and means are disclosed for selectively filtering a wave modulated with pulses differing in amplitude so as to eliminate unwanted pulses whether or not they are of less or greater amplitude than wanted pulses.

It is an object of my invention to provide an additional method and means for accomplishing the same result.

Another object of my invention is to provide a method and means for amplifying a pulse modulated wave to reduce the amplitude of the pulses greater than a given amplitude.

The reduction in amplitude or the elimination of the pulses of amplitude greater than a given amplitude such as the amplitude of a wanted pulse is accomplished in accordance with my invention by applying the pulse modulated wave to an amplifier having an input-output characteristic such that an increase of input potential causes the output thereof to increase to a maximum and then to decrease toward zero. The gain of the amplifier may be adjusted so that the peak of the wanted pulse lies near the maximum of the input-output characteristic so that the wanted pulse is amplified a desired value and the pulses of greater amplitude are distorted. The distortion produces sharp pulse portions defining the leading and trailing edges of the larger pulses according to the amounts they extend beyond the maximum of the amplifier input-output characteristic. These sharp pulse portions are limited in amplitude by the maximum of the input-output characteristic of the amplifier. The amplitude of the sharp portions may be reduced further by passing the output of the amplifier through a filter to eliminate the higher harmonics. This reduces the amplitude of the sharper pulse portions with respect to the amplitude of the wanted pulse which, of course, is of greater duration than the duration of the sharp pulse portions. By proper adjustment of the gain of the amplifier and the proper filtering of the output thereof, an output will be obtained in which the wanted pulses have greater amplitude than the unwanted pulses. By clipping this pulse output at a level beyond the maximum amplitude of the unwanted pulses, a pulse wave will be obtained containing the pulse energy according to the occurrence of the

2

wanted pulses with substantially a complete elimination of unwanted pulses.

For a further understanding of the invention reference may be had to the following detailed description to be read in connection with the accompanying drawing, in which:

Fig. 1 is a schematic illustration of a circuit in accordance with my invention, and

Fig. 2 is a graphical illustration showing the pulse reduction and eliminating features of the invention.

Referring to Fig. 1, the pulse reducing and eliminating system of my invention comprises an amplifier circuit 10, a filter 12 and a clipper 13. The amplifier circuit may comprise any arrangement of elements whereby an input-output characteristic is established so that an increase of input potential causes the output to increase to maximum and then to decrease toward zero. Such a characteristic is illustrated at 15 in Fig. 2.

For purposes of illustration, I have shown in Fig. 1 an amplifier circuit comprising an input vacuum tube 16 having zero bias and two amplifier tubes 21 and 22 the grids 23 and 24 of which are connected to the anode 17 and the cathode 18 of the tube 16 in push-pull arrangement. The anode 17 is provided with a positive bias through a resistor 19, and is connected to the grid 23 through a coupling condenser 25. The grid 23 is provided with a negative bias C_1 through a resistor 27. The cathode 18 of the tube 16 is connected through a resistor 28 to ground. The cathode 18 is also connected to the grid 24 through a coupling condenser 29. The grid 24 is biased negatively by a potential C_2 through a resistor 30. The cathodes of the tubes 21 and 22 are connected together and grounded at 32. The anodes or plates of the tubes 21 and 22 are connected together to provide an outlet 33, the latter being connected to a positive potential through a resistor 34.

The input tube 16 operates to apply the input pulse or potential to tube 22 without inversion of polarity and simultaneously to apply the input potential to tube 21 with inverted polarity. In the absence of an input potential, the tube 21 is biased beyond plate cut-off while the tube 22 is biased to a value permitting a normal plate current. As the grid 14 of tube 16 is made increasingly negative by an increasing input potential, the grid 24 of tube 22 is made more and more negative thereby resulting in a reduction of its plate current. This causes a rising potential to occur at the plate output connection 33 as indicated between points 40 and 41 on the

curve 15 of Fig. 2. At point 41, tube 22 is at plate current cut-off. During the interval between 40 and 41 the voltage on the grid 23 of tube 21 increases in a positive direction, but since b is C₁ is so chosen to cause the tube 21 to remain at cut-off, the tube contributes nothing to this part of the curve. However, the instant tube 22 reaches cut-off, the grid potential of tube 21 begins to rise above cut-off. As the amplitude of the input potential continues to rise, the grid 23 of tube 21 becomes more and more positive and the tube conducts more and more current causing the potential at the plate connection 33 to decrease as indicated between 41 and 42 on the curve 15. At point 42 the input potential has reached a value sufficient to cause cut-off of the tube 16 and any further increase in potential on the grid 14 of the tube 16 results in no further change in potential at 33.

While I have shown the increasing and decreasing portions of the characteristic curve 15 to have substantially the same slope in the inverse direction, it will be understood that the characteristics of the tubes may be such as to provide entirely different slopes and different maximum and minimum points 41 and 40, 42 respectively, for the curve. The main feature of the invention, however, is to provide the input and output characteristic curve with a maximum point whereby pulses applied to the amplifier extending in amplitude beyond the maximum point of the curve are distorted and limited in amplitude.

Assume that the input to the grid 14 of the tube 16 is a modulated wave having a series of pulses 51, 52, 53 and 54, with the pulse 51 repeated as indicated. The wave, of course, may contain other pulses which occur at random or at a given frequency not shown with the group illustrated in Fig. 2. The pulses illustrated, however, are representative in that the pulse 51 is the wanted pulse while the pulses 52, 53 and 54 are the unwanted pulses. The pulses 52 and 53 are of greater amplitude than the wanted pulse while the pulse 54 is of less amplitude.

To eliminate the unwanted pulses, the gain of the amplifier 10 is adjusted so that the amplitude of the wanted pulse 51 is brought near and preferably slightly under the maximum point 41 of the input-output characteristic of the amplifier. The output pulse 51a is thereby produced in substantially the same shape as the input pulse 51. The pulse 52, however, is greatly distorted since it extends beyond the maximum point 41 and in fact beyond the zero point 42 of the curve. When this pulse is applied to the amplifier, the tube 21 passes the pulse potential up to the maximum level as indicated at a thereby producing a leading edge 55. Then the tube 22 takes over for the potential of the pulse above the level a thereby providing a return trailing edge 56 to zero. The decreasing potential on the trailing sides of the pulse 52 provides a second sharp pulse from zero as indicated by the leading edge 57 which extends to the level a for the maximum point 41. The tube 21 then takes over for the remaining decrease in potential below the level a thereby providing a trailing edge 58. Thus, the distorted pulse output for the large input pulse 52 provides a sharp pulse 52a which defines the leading edge of the input pulse 52 and a second sharp pulse 52b which defines the trailing edge thereof. The amplitudes of the pulses 52a and 52b are limited by the maximum point 41 of the characteristic curve 15.

The third input pulse 53, while of amplitude

greater than the pulse 51, does not extend through the decreasing portion between the maximum 41 and the zero point 42 of the characteristic curve 15. The output for the pulse 53 is shown at 53a. The leading edge of the pulse 53 provides a leading edge 60 for the pulse 53a which extends to the level a. Since the input pulse 53 extends above the maximum level a the tube 22 takes over and provides a decreasing or trailing edge 61 until the top level b of the pulse 53 is reached. This provides a sharp pulse portion overlying the leading edge 60. When the trailing edge of the input pulse 53 decreases the potential input applied to the amplifier, a return through the characteristic curve is obtained whereby a second sharp pulse portion 64 is formed defining the trailing edge of the output pulse 53a. The pulse 53 is thus distorted by the portion thereof extending beyond the maximum 41 of the characteristic curve 15.

The pulse 54 of amplitude less than the wanted pulse 51 provides an output which in accordance with the adjustment of the amplifier may be smaller as indicated at 54a than the input pulse 54.

As shown in Fig. 2, the pulse portions 52a, 52b, 63 and 64 defining the leading and trailing edges of the larger input pulses 52 and 53 respectively, are sharper pulses than the pulse output 51a of the wanted pulse 51. By suitably filtering out the higher harmonics, the sharp pulse portions 52a, 52b, 63 and 64 are reduced in amplitude as indicated by the wave 70. By clipping the wave 70 along a level 71 preferably above the greatest amplitude of the unwanted pulses, a final output wave 80 is obtained having pulse energy 81 which correspond to the pulses 51. Thus, the interfering pulses 52, 53 and 54 are effectively eliminated. The output pulse energy 81 may, of course, be sharpened or otherwise treated as may be desired depending on the use intended for the pulse energy thus obtained.

While I have described the principles of my invention in connection with a specific system, it will be understood that the system herein shown and described is not to be considered as a limitation on the scope of my invention as set forth in the objects thereof and in the appended claims.

I claim:

1. A method of eliminating from a wave modulated with substantially unidirectional pulses of different amplitude and of appreciable duration those pulses of greater and lesser amplitude than a wanted pulse comprising distorting the pulses of greater amplitude by producing sharp pulse portions having high harmonic content from the leading and trailing edges of the pulses of greater amplitude while leaving the wanted pulse substantially unchanged in form, filtering said waves to eliminate the higher harmonics of the pulses thereby reducing the amplitudes of the distorted pulses with respect to the amplitude of the wanted pulse, and clipping the output pulses at a level above the maximum output amplitude of the unwanted pulses.

2. A method of eliminating from the wave modulated with pulses of different amplitude and of appreciable duration those pulses of greater and lesser amplitude than a wanted pulse comprising applying the wave to an amplifier having an input-output characteristic in which an increase of input potential causes the output to increase to maximum and then to decrease toward zero, adjusting the gain of the amplifier so that

the peak of the wanted pulse lies near the maximum of said characteristic so that the wanted pulse is amplified a desired amount without substantial distortion and the pulses of greater amplitude are distorted resulting in sharp pulse portions having high harmonic content and defining the leading and trailing edges thereof according to the amounts they extend beyond said maximum, filtering the pulses to eliminate the higher harmonics thereby reducing the amplitudes of the distorted pulses with respect to the amplitude of the wanted pulse, and clipping the output pulses at a level above the maximum output amplitude of the unwanted pulses.

3. A system for selecting a wanted pulse of appreciable duration from a wave modulated with pulses of different amplitude having pulses of greater and lesser amplitude than a wanted pulse comprising an amplifier to distort the pulses of greater amplitude than the wanted pulse, the distortion producing sharp pulse portions of high harmonic content defining the leading and trailing edges of the pulses of greater amplitude, means to filter the pulses to eliminate the higher harmonics and thereby reduce the amplitudes of the distorted pulses with respect to the amplitude of said wanted pulse, and means to clip the output pulses at a level above the maximum output amplitude of the unwanted pulses.

4. The system defined in claim 3 wherein the amplifier comprises a pair of tubes connected in

push-pull arrangement, one of the tubes providing an input-output characteristic extending from zero to a maximum and the other of said tubes providing an input-output characteristic extending from said maximum to zero.

5. The system defined in claim 3 wherein the amplifier comprises a circuit having a pair of tubes connected in push-pull arrangement and a third tube to control the input potential on said tubes so as to produce an input-output characteristic extending from a minimum value to a maximum value and then from said maximum value toward said minimum value.

6. A method of eliminating from a wave modulated with substantially unidirectional pulses of different amplitude having a predetermined fundamental frequency content, those pulses having amplitude greater or lesser than a predetermined level, comprising distorting pulses above a given amplitude thereby producing sharp pulse portions and relatively increasing the harmonic content in varying degree, from the leading and trailing edges of the pulses above the given amplitude, filtering said waves to eliminate the higher harmonics of the pulses thereby reducing the amplitude of the distorted pulses substantially proportionally to their harmonic content, and clipping the output pulses at a level above that of the greater amplitude pulses after reduction.
